UNITED STATES PATENT OFFICE.

WILLIAM L. ISBILLS, OF BAYONNE, NEW JERSEY.

DESIGN FOR A CURTAIN-CARRIER BLOCK.

SPECIFICATION forming part of Design No. 32,059, dated January 2, 1900.

Application filed November 22, 1899. Serial No. 737,959. Term of patent 14 years.

To all whom it may concern:

Be it known that I, WILLIAM L. ISBILLS, a citizen of the United States, residing at Bayonne, in the county of Hudson and State of New Jersey, have invented and produced a new and original Design for Curtain-Carrier Blocks, of which the following is a specification, reference being had to the accompanying drawings, forming part thereof.

Figure 1 is a side view; Fig. 2, an end view, and Fig. 3 a plan view from below.

Similar letters of reference indicate corresponding parts in all the figures where they appear.

As shown in the drawings, the leading or material feature of my design consists of two parallel semicylindrical offsets or beads A', extending longitudinally the whole length of the block A a little below the mid-height. In

the center of the bottom, narrower than the top by reason of the offsets, is a ring B, lying in the plane longitudinal of the block. The open interior of this ring is marked b.

This design is applicable to curtain-carriers of various sizes and of any or all materials. 25

Having described my invention, what I claim as new, and desire to secure by Letters Patent, is—

The design for a curtain-carrier block, as herein shown and described. 30

In testimony that I claim the invention above set forth I affix my signature in presence of two witnesses.

WILLIAM L. ISBILLS.

Witnesses:

J. B. CLAUTICE,
C. A. WEED.
